UNITED STATES PATENT OFFICE.

HANS BARLACH, OF CHARKOW, RUSSIA.

WATER-TUBE SECTIONAL BOILER.

1,030,452.

Specification of Letters Patent. Patented June 25, 1912.

Application filed July 27, 1910. Serial No. 574,166.

To all whom it may concern:

Be it known that I, HANS BARLACH, a subject of the German Emperor, residing at Charkow, in the Empire of Russia, have invented certain new and useful Improvements in Water-Tube Sectional Boilers, of which the following is a full, clear, and exact description.

My invention refers to a water-tube sectional boiler and is for the purpose of obtaining a very compact construction and at the same time a large heating surface, accompanied by great solidity and cheapness in the cost of manufacture. The arrangement according to the invention is more particularly suitable for central heating, but can, however, be used with advantage for other purposes.

The sectional boiler consists of tubular elements arranged beside each other in vertical planes, which elements, according to the present invention, form with their outer portions, water-cooled throughout the whole surface, the jacketing of the boiler, and their inner portions form the walls of the feed chamber, fire box and smoke-flues and preferably also the grate. The elements are made of wrought iron. The openings for the gas and smoke are formed by constricting, bending or flattening the tubes or in some similar manner. The tubes will preferably be of polygonal cross section, and the tubes are so set together that more than the half of their surface can be utilized as heating surface. In order to increase the heating surface the tubes may be provided with ribs, the height of which will amount to $2\frac{1}{2}$ to 3 times the diameter of the tube.

I shall now describe my invention with reference to the accompanying drawing in which:

Figure 1 shows a cross section through a heating device according to the present invention and formed of two different shaped tubular elements. Fig. 2 is a cross section through the device vertical to the plane of section according to Fig. 1. Figs. 3 and 4 are side views of both the tubular elements, of which the device according to Figs. 1 and 2 is composed. Figs. 5 to 11 show further modifications in cross section differing es-

sentially by the means which are employed for forming the smoke openings. In the forms of construction according to Figs. 1 to 11 the tubes are of circular cross section. Fig. 12 shows a further modification of the invention in which the tubes are of rectangular cross section. Figs. 13^a and 13^b are views in transverse section through coacting tubes of polygonal cross section suitable for the construction of the tubular elements. When using this cross section for the tubes a greater portion of the walls of the tube may be utilized as heating surfaces than would be possible when using the circular cross section.

In the device according to Figs. 1 to 4 water flows from a lower water supply pipe *a* into the distributing pipe *b* of the tubular elements, which in its first portion constitutes the water grate. The cooling water flows from the distributing pipe *b* owing to the ascending power imparted to it by heating through the jacketing and branch pipes *c*, *d*, *e*, *f*, or *c*, *d'*, *e*, *f* to the escape pipe *g*. By setting together the tubular elements a fuel chamber *h* and smoke flues *i* are formed. The smoke flues are separated from the chamber by the tubes *d*, *d'* situated close beside each other. The passage of the smoke from the fuel chamber to the flues is rendered possible owing to the special formation of the pipes *d*, *d'* which has as result that in their upper portion the tubes *d*, *d'* are not situated beside each other but an intermediate space is formed between the tubes *d* and *d'*. As may be seen from the drawing for this purpose the tubes *d* are bent at right angles whereas the tubes *d'* are perfectly straight. The outer walls of the feed chamber are formed by the water-tubes *c* situated quite close to each other and the outer walls of the smoke flues are formed by the tubes *f* also situated close to each other. In Fig. 5 the smoke openings are also formed by bending the tubes *d* at right angles whereas the tubes *d'* are perfectly straight. Contrary to the forms of constructions shown in Figs. 1 to 4, however, smoke flues are arranged on both sides of the stove.

In Fig. 6 the tubes *d* as well as the tubes

d^4 are bent at an obtuse angle in their upper portion for the purpose of forming the openings for the smoke.

In Fig. 7 the tubes e bent at right angles have their outlet in the upper portion of the tubes d^5 , d^6 . The tubes d^5 , d^6 are also bent at right angles in their lower portion of the pipe e . The smoke openings in this case are formed by arranging the horizontally running portions of the tubes d^5 , d^6 or of the tubes e staggered to each other.

Fig. 8 shows a boiler on the upper surface of which a cooking device is to be arranged. In order that the hot plate may be attacked directly by the fire the upper jacketing tubes are dispensed with. With the same object in view upper jacketing tubes might also be employed which are of less cross section than the side jacketing tubes. The smoke openings are formed in Fig. 8 as well as in Fig. 9 in this that less cross section is given to the tubes connecting the tubes d^7 , e' .

In Fig. 10 the smoke openings are formed by constricting the upper portion of the tube d^8 .

In Fig. 11 the inner vertically rising tubes are dispensed with and are substituted by horizontally running tubes k . In this case the smoke openings are formed by dispensing with the upper horizontal tubes.

In Fig. 12, as above mentioned, tubes of rectangular cross section are used for forming the tubular elements. The smoke flues g are in this case formed by the ribs r of the tubes t and the smoke openings by dispensing with the ribs of the tubes at the corresponding spots.

In Fig. 13^a, various cross sections of tubes are shown. By using these cross sections for the tubes a relatively large heating surface is obtained. The cross sections shown can be used with any of the forms of construction shown in Fig. 1 to 11 and more particularly for the jacketing tubes. They are so arranged that the flat portion of the upper surface is situated outwards whereas the curved portion of the upper surface is situated inwards.

Fig. 13^b shows several different cross sections of tubes that can be employed in the form of construction shown in Fig. 12, or in like forms of construction, in which chambers are formed longitudinally by tubes t , having ribs r , formed integral therewith and when disposed in abutting relation to each other, as shown in Fig. 13 of the drawing, form flues g for the gases from the fire-box. Because of the disposition and shape of the tubes t , a greater area of surface is presented to be acted upon by the gases than would be with the common type of tube, and consequently the capacity of the boiler is increased accordingly. The pro-

portion of the ribs in height are substantially two and one half to three times the diameter of the tubes, in order to obtain the most practical results.

Having thus described my invention what I claim as new and desire to secure by Letter Patent is:

1. In a water-tube boiler, the combination of a plurality of sections provided with inlet and outlet means, said sections comprising a plurality of upright conducting members arranged to form the jacketing of the boiler, and intermediate conducting members in communication with said upright conducting members, and arranged in contact with each other to form a wall of a flue separate from the fire-box, said intermediate conducting members being alternately branched in different directions to form a communication between the fire-box and the said flue. 75

2. In a water-tube boiler, the combination of a plurality of sections provided with inlet and outlet means, said sections comprising a plurality of pairs of upright conducting members forming the jacketing of the boiler, cross conducting members, spaced apart, connecting the said upright conducting members of each pair and arranged below the fire-box of the boiler, and conducting members intermediate the said upright conducting members, in communication with said cross members, and in contact with each other to form a wall of a flue adjacent to the fire-box, said intermediate conducting members being alternately branched in different directions to form a communication between the fire-box and the said flue. 85

3. In a water-tube boiler, the combination of a plurality of sections provided with inlet and outlet means, said sections comprising a plurality of tubular conducting members arranged to form the jacketing of the boiler, and conducting members in communication with said tubular conducting members and provided with longitudinal channels formed by longitudinal hollow ribs which, arranged in abutting relation to each other, form a plurality of flues in communication with the fire-box, said ribs being in height substantially two and one half to three times the diameter of said conducting members they are formed integral with. 105

4. In a water tube boiler, the combination, of a plurality of sections provided with inlet and outlet means, said sections comprising a plurality of upright conducting members disposed to form jacketing of the boiler, and intermediate conducting members in communication with said upright conducting members and arranged in contact with each other to form a wall of a flue separate from the fire box, said intermediate conducting members being alternately 110

branched to extend in different planes, at their upper portions, to form a communication between the fire box and said flue.

5. In a water tube boiler, the combination, a boiler jacketing for containing fluid, a plurality of conducting members in communication with said jacketing and arranged in contact with each other to form a wall of a flue separate from the fire box, said conducting members being alternately branched

to extend in different planes from each other, at their upper portions, to form a communication between the fire box and said flue.

In testimony whereof I affix my signature 15 in presence of two witnesses.

HANS BARLACH.
